UNITED STATES PATENT OFFICE.

LOUIS KELLNER, OF NEW YORK, N. Y.

ELECTRIC SWITCH.

1,354,763.

Specification of Letters Patent. Patented Oct. 5, 1920.

Application filed June 26, 1919. Serial No. 306,903.

To all whom it may concern:

Be it known that I, LOUIS KELLNER, a citizen of the United States, and resident of the borough of Manhattan, city, county, and State of New York, have invented certain new and useful Improvements in Electric Switches, (Case J,) of which the following is a specification.

This invention relates to improvements in armored or safety switches and is particularly applicable to fused armored switches.

In the accompanying drawings a triple-pole, single-throw switch is shown, but it will be obvious that the invention may be embodied in switches of various other constructions.

The invention has for one of its objects the provision of simple and effective means for preventing access to the live parts of a switch while current is passing through the switch, and for preventing interference with the operation of movable parts of the switch.

Another object of the invention is to provide a fused switch so constructed that access to the fuse or fuses, the fuse clips or supports, and other live parts, is impossible except when the switch has been operated through the medium of its operating handle to break the circuit.

Another object of the invention is to provide a fuse-inclosing means having a movable closure portion and shiftable by the switch mechanism, when the same is operated to close the circuit, to a position in which movement of the closure to its open position is impossible.

A further object of the invention is to provide a switch having oscillatory terminal-bridging means, fuses and fuse-inclosing means partaking of the oscillating movement of the bridging means, and a stationary abutment or stop, the fuse-inclosing means having a hinged section which is held in closed position by said abutment when the bridging means is in "on" position.

A further important object of the invention is to provide fuse-inclosing means movable with the terminal-bridging means of a switch and having a movable section or closure, and means adapted to prevent an opening movement of the closure when the bridging means is in "on" position, and to automatically move the closure to closed position when the switch is operated to

close the circuit without first closing said movable section or closure.

Another object of the invention is to provide a switch having fuse-inclosing means and a fuse movable with the terminal-bridging means, and a casing inclosing the fuse-inclosing means and all of the switch mechanism except the operating handle, said casing having a closure adapted to be locked to prevent access to the line terminals and the bridging means.

In the drawings, Figure 1 is a longitudinal section on the line I—I of Fig. 4, showing the switch in "on" position;

Fig. 2 a similar view showing the switch in "off" position and the movable section of the fuse-inclosing means in open position;

Fig. 3 a transverse section on the line III—III of Fig. 1;

Fig. 4 a view partly in transverse section and partly in end elevation, showing the switch in "on" position;

Fig. 5 a detail view of a part of the switch-operating mechanism;

Fig. 6 a section on the line VI—VI of Fig. 5;

Figs. 7, 8, 9 and 10 detail perspective views of parts of the switch-operating mechanism;

Fig. 11 a plan view of the fuse-inclosing means;

Fig. 12 a fragmentary section on the line XII—XII of Fig. 17;

Fig. 13 a view similar to Fig. 12, showing the parts in the position assumed thereby when the switch is in "off" position;

Fig. 14 a section on the line XIV—XIV of Fig. 17;

Fig. 15 a section on the line XV—XV of Fig. 17;

Fig. 16 a section on the line XVI—XVI of Fig. 17; and

Fig. 17 a fragmentary horizontal section on the line XVII—XVII of Fig. 4.

The entire switch mechanism, excepting the operating handle 1, is inclosed within an outer casing of elongated rectangular form having a base plate 2 formed of slate, porcelain, or other suitable insulating material, side and end walls 3 and 4, preferably formed of sheet metal, and a metallic cover 5 hinged at 6 to one of the end walls 4 of the casing. A hasp 7 is hinged to the free end of the cover 5 and engages over a staple 8 fixed to the adjacent end wall 4. A suitable padlock 9 is provided for pre-

venting opening of the cover 5 by unauthorized persons. One set of stationary contacts or line terminals 10 are fixed to the base 2 adjacent one end of the casing, and 5 the other set of stationary contacts or line terminals 11 are fixed to the inner side of a block 12 of insulating material which is secured to a metallic plate 13. The plate 13 is removably held by screws 14 to 10 brackets 15 secured to the side walls 3 of the casing adjacent the cover 5 and at the opposite end of the casing from the contacts 10.

Each of the movable contacts comprises a 15 brush formed of a plurality of spring metal plates of different lengths. One set of movable contacts 16 are adapted to engage the contacts 10, and the other set of movable contacts 17 are adapted to engage the contacts 11. The contacts 16 are held by pairs of rivets 18 to the inner side of a rocking support or block 19 formed of insulating material, and the contacts 17 are held to the under side of block 19 by pairs of rivets 20. 25 A set of fuse clips 21 are held to the outer side of the rocking support 19 by the rivets 18 which also serve to electrically connect the contacts 16 and fuse clips 21. A set of fuse clips 22 are held to the outer side of 30 support 19 by the rivets 20 which also serve to electrically connect said clips 22 with the contacts 17. The clips 21 and 22 are electrically connected by fuses 23 which are removably supported by the clips in the usual 35 manner.

The support or block 19 is rigidly held intermediate its ends to a rocking or oscillating bar 24. The bar 24 is formed at one end with a shaft 25 journaled in a bracket 40 26 held to the base 2, and said bar is formed at its opposite end with a shaft 27. A sleeve 29 surrounds shaft 27 substantially throughout the length of the shaft, the sleeve and shaft extending through a bearing in a 45 bracket 28 held to the base 2. The outer ends of the sleeve and shaft project through an aperture 30 in the adjacent side wall 3 of the outer casing, and the switch-operating handle 1 is fixed on the outer end of the sleeve 50 29 by a suitable locking screw 31. The sleeve 29 is formed with an enlarged portion 32 intermediate its ends, said enlarged portion of the sleeve being formed at its ends with reduced angular portions 33 and 34. A spring- 55 winding member 35 is rigidly held on the angular portion 34 of the sleeve, said member being formed with an arm, pin or projection 36 extending laterally inwardly between the free depending ends 37^a and 37^b 60 of a motor spring 37 which is coiled about the enlarged portion 32 of the sleeve.

A disk 38 is rigidly held to one end of the rocking bar 24 by suitable fastening devices 39, said disk being formed with a central aperture through which shaft 27 ex-

tends and being adapted to rotate relatively to sleeve 29 in opposite directions in a substantially circular opening 40 in a plate 41 formed integrally with the base of bracket 28. A pair of reciprocable latch bolts 42 and 43 are slidably mounted in ways 44 and 45 formed in one face of the disk 38, and said bolts are held in the ways by a face plate 46 fixed to the disk. The latch bolts are normally forced outwardly by springs 47 and 48, the sliding movement of the bolts being limited by pins 49 and 50 projecting outwardly from the bolts 42 and 43, respectively, through slots 51 and 52 in the face plate 46. Latch bolt 42 is adapted to be retracted by a releasing lever 53 pivotally held intermediate its ends to disk 38 by a pivot pin 54 and provided at its inner end with a slot 55 through which the pin 49 on the latch bolt extends. Latch bolt 43 is adapted 80 to be retracted by a releasing lever 56 pivotally held intermediate its ends to disk 38 by a pin 57 and provided at its inner end with a slot 58 through which pin 50 on the bolt extends. The latch bolts are adapted 85 to engage opposite sides of either of two locking lugs or stops 59 and 60 projecting into a segmental recess 61 formed by cutting away the plate 41 at one side of the opening 40. The plate 41 is also cut away to form a 95 segmental recess 62 opposite the recess 61 in which a stop or lug 63 formed on the disk 38 is adapted to travel, said stop being adapted to engage shoulders 64 and 65 at opposite ends of the recess 62 to positively limit the 100 extent of rotation of disk 38 in either direction. The recess 62, shoulders 64 and 65, and stop 63 may be omitted if desired. The disk 38 is provided with an arm, pin or projection 66 extending outwardly between the 105 ends 37^a and 37^b of the motor spring 37. The latch-releasing levers are operated by a trip device or plate 67 fixed on the angular portion 33 of sleeve 29 and formed with a pair of inwardly extending lugs or projections 68 and 69 adapted to engage and rock the releasing levers 53 and 56, respectively. 110

The fuses, fuse clips, and outer ends of rivets 18 and 20 are inclosed with a semi-cylindrical inclosing casing formed by the 115 rocking support 19, and a metal housing or inner casing having end walls 70 and a curved top wall having a fixed section 71 and a movable section or closure 72 hinged at 73 and normally held in closed position 120 by a spring-pressed latch 74 held to the top section 71 and adapted to engage in an aperture 75 in closure 72. The latch 74 may be of any suitable construction. The hinged wall 5 of the outer casing is provided with a rectangular opening slightly larger than the hinged section 72 of the fuse-inclosing means, said wall 5 being formed with inclined flanges 76 at the opposite sides of 125 said opening, extending inwardly within the 126

outer casing into close relation with the side walls 70 of the fuse-inclosing means. At 5 one end of the opening the top wall 5 is formed with an inwardly extending flange 77 the inner edge of which is substantially flush with the outer side of the hinged section 72 of the fuse-inclosing casing, and at the opposite end of the opening said wall 5 is formed with a flange 78 the inner edge of 10 which is substantially flush with the fixed section 71 of the fuse-inclosing casing. When the switch is in "off" position the hinged section 72 of the fuse casing is in complete register with the opening in the 15 wall 5 of the outer casing and is free to be swung outwardly as shown in Fig. 2, to permit access to the fuses upon rocking the hooked end of the latch to release said hinged section. When the switch is in "on" 20 position, as shown in Fig. 1, the hinge 73 of section 72 is moved out of register with the opening in wall 5 to a point within the outer casing, and an intermediate portion of said hinged section 72 is brought into register 25 with a fixed abutment or stop formed by the inner end of flange 77, thus preventing opening of the hinged section 72 until the switch is operated to break the circuit. It will be observed also that if the switch should be 30 operated to close the circuit without first closing section 72, said section will be automatically forced to closed position by flange 77 and will be locked in closed position by latch 74.

35 With the parts in the position shown in Figs. 1, 4, 12, and 14 to 17, the switch mechanism may be operated to break the circuit by swinging the handle 1 in a clockwise direction, thus rotating sleeve 29 and the 40 spring winding device 35 relatively to shaft 27 and disk 38 and causing arm 36 to move the end 37^a of the spring 37 away from the end 37^b of the spring to store power in said spring. The rotation of sleeve 29 also causes 45 the trip device 67 to rotate in a clockwise direction, the lug 68 of the trip, at the conclusion of the power storing movement of handle 1, engaging and rocking the releasing lever 53 to cause the same to force latch bolt 42 inwardly out of engagement with stop 59. When latch bolt 42 is released from stop 59 the disk 38 will be rotated in a clockwise direction by reason of the engagement of end 37^b of spring 37 with the pin 66, thus 50 rocking bar 24, the support 19 and parts mounted thereon to the position shown in Figs. 2 and 13, the latch 43 riding under stop 60 and snapping back of the same to lock the parts in "off" position. At the 55 same time, latch 42 engages the opposite side of stop 60 to prevent further rotation of disk 38. To restore the switch to "on" position the handle 1 is swung in the reverse direction, the arm 36 advancing end 37^b of spring 37 to wind the spring, and lug 69 of 60

the trip device 67 operating releasing lever 56 to retract latch bolt 43, whereupon the support 19 will be rocked in a counter-clockwise position and the latch bolts will again engage stop 59. The outer sides of 65 the outer ends of the latch bolts are beveled as shown to permit the bolt 42 to ride under stop 59 and bolt 43 to ride under stop 60 during movement of the switch to "on" and "off" positions, respectively. It will be observed that the rocking support is positively locked against movement in both its "on" and "off" positions, and can only be moved when the handle 1 is shifted sufficiently to insure a snap action of the switch to either 70 "on" or "off" position, and that it is, therefore, impossible to obtain access to the interior of the fuse-inclosing casing except when the switch has been shifted to and locked in its "on" position by an operation 75 of the handle 1.

In order to prevent accidental interference with the operation of the movable parts of the switch when handle 1 is actuated, a cover or supplemental door 79 is 80 hinged at 80 to the cover plate 5 of the outer casing, said cover having a curved top plate extending over the opening in cover plate 5 and having segmental side plates engaging the cover plate along opposite sides of 85 the opening. The hinge 80 is preferably a spring hinge serving to normally hold the supplemental door 79 closed. The door or cover 79 prevents interference with the movement of the rocking support by engagement of a part of the body of a person, or engagement of any object, with the rocking fuse-inclosing casing, since the spring hinge 80 will automatically close the door 90 when the door is released and prevent anything engaging the fuse casing. The fuse-inclosing casing is preferably provided with the signs 81 and 82 adapted to register with a glass panel 83 in the supplemental cover 79 when the switch is in its "off" and 95 "on" positions, respectively.

100 It will be observed that access to the movable and stationary contacts is impossible except by unlocking the padlock 9 and opening cover 5. It will also be noted that the contacts 11, the block 12 and plate 13 may be readily removed as a unit when cover 5 is opened to permit convenient access to the contacts 11 for connecting the line wires therewith or for any other purpose.

115 It will be observed also that the movable contacts are held to the rotatable support at opposite sides of the support, and that the fuses are electrically connected at their 120 ends with the movable contacts and are mounted on the support transversely of the axis of rotation of the support. This arrangement is highly advantageous since the fuses move endwise when the support is 125 130

shifted, instead of sidewise, and the shocks due to sudden starting and stopping of the support are taken up longitudinally of the fuses. By thus mounting the fuses to move endwise, rupturing of the fuses when near the melting point, which might occur if the fuses were subjected to transverse strains, is avoided.

What I claim is:

- 10 1. In an electric switch, the combination of means inclosing live parts of the switch and having a movable closure member, stationary contacts, contact bridging means, means for rotating the bridging means to make and break the circuit, said closure member being movable with the bridging means and shiftable relatively thereto to expose the inclosed live parts of the switch, and means for holding said closure in closed position when the bridging means is in circuit closing position, said closure holding means being disengaged from the closure when the bridging means is in circuit breaking position.
- 15 2. In an electric switch, the combination of means inclosing live parts of the switch, stationary contacts, contact-bridging means, means for rotating the bridging means to make and break the circuit, a closure member movable with the bridging means, and a relatively stationary abutment adapted to engage the closure member when the bridging means is rotated to "on" position to prevent opening of the closure member.
- 20 3. In an electric switch, the combination of stationary contacts, contact-bridging means, a rotatable support for the bridging means, means including an operating handle for rotating said support to make and break the circuit, a casing inclosing the entire switch mechanism except the operating handle and having an opening in one wall thereof, a closure member pivotally mounted on the support and adapted to be swung outwardly through said opening when the bridging means is in "off" position, and an abutment on the casing adapted to engage said closure member when the bridging means is in "on" position to prevent opening of the closure member.
- 25 4. In an electric switch, the combination of line terminals, a rotatable support, fused terminal-bridging means mounted on the support, a casing mounted on the support inclosing the fuse and fuse connections and having a movable closure section, means for rotating the support to make and break the circuit, and means out of the path of the opening movement of said closure section when the circuit is broken adapted to prevent opening of the closure section when the support is rotated to shift the bridging means to circuit-closing position.
- 30 5. In an electric switch, the combination of line terminals, a rotatable support, fused

terminal-bridging means mounted on the support, a casing mounted on the support inclosing the fuse and fuse connections and having a movable closure section, means for rotating the support, and a stationary abutment adapted to engage the closure section when the bridging means is moved to "on" position to hold the closure section in closed position.

6. In an electric switch, the combination of line terminals, a rotatable support, fused terminal-bridging means mounted on the support, a casing mounted on the support inclosing the fuse and fuse connections and having a hinged section shiftable to permit access to the fuse and connections when the bridging means is in "off" position, means for rotating the support to move the bridging means to "on" and "off" positions, and means for preventing opening of the hinged section when the bridging means is in "on" position.

7. In an electric switch, the combination of line terminals, a rotatable support, fused terminal-bridging means mounted on the support, a casing mounted on the support inclosing the fuse and fuse connections and having a hinged section shiftable to permit access to the fuse and connections when the bridging means is in "off" position, means for rotating the support to move the bridging means to "on" and "off" positions, and a stationary abutment adapted to prevent an opening movement of the hinged section when the bridging means is moved to "on" position.

8. In an electric switch, the combination of line terminals, a rotatable support, fused terminal-bridging means mounted on the support, a casing mounted on the support inclosing the fuse and fuse connections and having a hinged section shiftable to permit access to the fuse and connections when the bridging means is in "off" position, an operating handle, means controlled by the handle for rotating the support, means for automatically locking the support in its "on" and "off" positions, means controlled by movement of the handle to a position to shift the support to "on" or "off" position for releasing the support, and means for engaging the hinged section when the support is moved to "on" position to prevent opening of said section.

9. In an electric switch, the combination of stationary contacts, a rocking support, movable contacts held to said support, fuse-holding means mounted on the support and connected with the movable contacts, a fuse supported in the fuse-holding means, means mounted on the support inclosing the fuse and fuse-holding means and embodying a movable cover member, means for rocking the support to move the movable contacts into and out of engagement with the station-

- ary contacts, and stationary means adapted to engage said cover member when the movable contacts are in "on" position to prevent opening of the cover member.
5. 10. In an electric switch, the combination of stationary contacts, a rocking support, movable contacts held to said support, fuse-holding means mounted on the support and connected with the movable contacts, a fuse supported in the fuse-holding means, a casing mounted on the support inclosing the fuse and fuse-holding means and having a hinged section, means for rocking the support to move the movable contacts to "on" and "off" positions, and a stationary abutment adapted to engage the outer side of the hinged section when the movable contacts are in "on" position to prevent opening of said section.
10. 11. In an electric switch, the combination of stationary contacts, a rocking support, movable contacts held to said support, fuse-holding means mounted on the support and connected with the movable contacts, a fuse supported in the fuse-holding means, a casing mounted on the support inclosing the fuse and fuse-holding means and having a hinged section, means for rocking the support to move the movable contacts to "on" and "off" positions, and a stationary abutment adapted to engage the outer side of the hinged section when the movable contacts are in "on" position to prevent opening of said section, said abutment being adapted to force the hinged section to closed position upon an operation of the switch to close the circuit with said hinged section in open position.
12. In an electric switch, the combination of stationary contacts, a rocking support, movable contacts held to said support, fuse-holding means mounted on the support and connected with the movable contacts, a fuse supported in the fuse-holding means, an inner casing mounted on the support inclosing the fuse and fuse-holding means and having a hinged section, an operating handle, means operated by said handle for rocking the support, and an outer casing inclosing the entire switch mechanism except said handle and having an opening in one wall through which the hinged section of the inner casing is adapted to swing when the switch is in "off" position, said hinged section being held against opening by engagement of the same with one edge of the opening in the outer casing when the switch is in "on" position.
13. In an electric switch, the combination of stationary contacts, a rocking support, movable contacts held to said support, fuse-holding means mounted on the support and connected with the movable contacts, a fuse supported in the fuse-holding means, an inner casing mounted on the support inclosing the fuse and fuse-holding means and having a hinged section, an operating handle, means operated by said handle for rocking the support, an outer casing inclosing the entire switch mechanism except said handle and having an opening in one wall through which the hinged section of the inner casing is adapted to swing when the switch is in "off" position, said hinged section being held against opening by engagement of the same with one edge of the opening in the outer casing when the switch is in "on" position, a closure member adapted to cover and uncover the opening in the outer casing, and a spring hinge connecting said member to the outer casing and normally holding the member in closed position.
14. In an electric switch, the combination of stationary contacts, a rocking support, movable contacts held to said support, fuse-holding means mounted on the support and connected with the movable contacts, a fuse supported in the fuse-holding means, an inner casing mounted on the support inclosing the fuse and fuse-holding means and having a hinged section, an operating handle, means operated by said handle for rocking the support, an outer casing inclosing the entire switch mechanism except said handle and having an opening in one wall through which the hinged section of the inner casing is adapted to swing when the switch is in "off" position, said hinged section being held against opening by engagement of the same with one edge of the opening in the outer casing when the switch is in "on" position, the wall of the outer casing having said opening therein being hinged to the casing, and means for locking the hinged wall of the outer casing in closed position.
15. In an electric switch, the combination of stationary contacts, a rocking support, movable contacts held to said support, fuse-holding means mounted on the support and connected with the movable contacts, a fuse supported in the fuse-holding means, an inner casing mounted on the support inclosing the fuse and fuse-holding means and having a hinged section, an operating handle, means operated by said handle for rocking the support, an outer casing inclosing the entire switch mechanism except said handle and having an opening in one wall through which the hinged section of the inner casing is adapted to swing when the switch is in "off" position, said hinged section being held against opening by engagement of the same with one edge of the opening in the outer casing when the switch is in "on" position, a closure member adapted to cover and uncover the opening in the outer casing, and a spring hinge connecting said member to the outer casing and normally holding the member in closed position.

16. In an electric switch, the combination of an outer casing having an opening in one wall, stationary contacts in said casing, a rotatable support in said casing, movable contacts held to said support, a fuse mounted on said support, an inner casing held to the support inclosing the fuse and having a hinged section, an operating handle located exteriorly of the outer casing, means 10 within the outer casing controlled by said handle for rotating the support to shift the movable contacts to "on" and "off" position and to move the hinge of the hinged section of the inner casing toward and from 15 one edge of the opening in the outer casing.
17. In an electric switch, the combination of a rotatable fuse-inclosing casing having a hinged door, a fuse mounted in the casing, contacts electrically connected with the 20 fuse and rotatable with the casing, stationary contacts adapted to be engaged by said movable contacts, a stationary abutment, and means for rotating the support, said fuse being mounted on the support transversely 25 of the axis of rotation of the support and the hinge of said door being parallel with

the axis of rotation of the support and movable between points at opposite sides of said abutment.

18. In an electric switch, the combination 30 of a rotatable support, contacts mounted on said support, a fuse mounted on the support transversely of the axis of rotation of the support, a casing mounted on the support inclosing the fuse and having a hinged closure section, stationary contacts, a stationary outer casing inclosing the stationary and movable contacts and the fuse-inclosing casing and having an opening in one wall thereof through which the closure section of 35 the fuse-inclosing casing may swing, and means embodying a handle located exteriorly of the outer casing for rotating the support to shift the movable contacts into and out of engagement with the stationary 40 contacts and to shift the hinge of the closure section of the fuse-inclosing casing toward and from one edge of the opening in the outer casing.

In testimony whereof I hereunto affix my 50 signature.

LOUIS KELLNER.
